UNITED STATES PATENT OFFICE

SOLOMON WEINBERG, OF PHILADELPHIA, PENNSYLVANIA, ASSIGNOR TO INDUSTRIAL BY-PRODUCTS & RESEARCH CORPORATION, OF PHILADELPHIA, PENNSYLVANIA, A CORPORATION OF DELAWARE

ABRASION TESTING MACHINE

Application filed May 27, 1930. Serial No. 386,510.

This invention relates to a machine for testing the abrasion resisting qualities of materials and more particularly relates to a machine for making a determination of the abrasion resisting qualities of fabrics.

The primary object of the present invention relates to the provision of a machine of this character in which uniformity of operation may be assured to give accurate indications of the resistant qualities of fabrics.

A further object relates to the provision of a machine in which the materials being tested are given relative curvilinear movements.

Another object of the invention relates to the provision of means whereby the machine may be opened to facilitate the replacement of materials being tested.

Still another object of the invention resides in the provision of a device for counting the reciprocations of the mechanism to determine the resistance of the materials being tested.

Other objects of the invention relating primarily to details of construction will be apparent from the following description read in conjunction with the accompanying drawings, in which:

Fig. 1 is a plan view of the improved machine.

Fig. 2 is a vertical section on line 2—2 of Fig. 1.

Fig. 3 is a vertical section on line 3—3 of Figs. 1 and 2.

The machine comprises a base 2 supporting a frame carrying the moving parts and providing a support for one of the portions of sheet material being tested. The frame 4 carried by the base is provided with upstanding ears in which is journaled a rod 6 to which are secured rearwardly extending frame members 8 connected at their rear ends by a rod 10 extending in parallelism with rod 6. Members 8 are bifurcated at their rear ends for the reception of bolts pivoted to the rear of frame 4 and provided with thumb nuts 12 which may be secured downwardly against members 8 to hold the frame formed by members 6, 8 and 10 in its lowered position, as shown in full lines in Fig. 3.

The forward ends of members 8 are extended upwardly to provide brackets sup-

porting the parallel rods 13, on which slides a segment 14 provided with an annular groove 16 in which rides a block 18 carried by a slide 20 adapted for reciprocating movement along the track 22 supported by the frame 4. Slide 20 is provided with a vertical slot in which slides block 24 pivotally secured to a link of a chain 26 trained about sprocket wheels 28, one of which is connected to a worm wheel 30 driven by worm 32 mounted on the shaft of a motor 33. As the motor operates the chain 26 continuously in one direction, the block 24 will carry slide 20 along track 22 and impart a reciprocating movement thereto, since block 24 is free to slide vertically within slot 20 as the chain which carries the block passes about sprocket wheels 28. The reciprocating movement of slide 20 is imparted to segment 14, to the opposite sides of which are connected the ends of a chain 34 trained around guiding sprockets 36 and secured to a slide 38, as shown in Fig. 1.

Slide 38 is provided, on its front and rear ends, with rollers 40 engaging rods 6 and 10 in a suitable anti-friction manner to provide free reciprocating movement of the slide opposite to that of segment 14. Brackets 42, extending upwardly from the sides of slide 38, are apertured to slide upon a guide rod 44 supported by members 8.

Slots 46 are provided in slide 38, extending in a direction transverse to that of its reciprocating movement. A supporting member 48 is provided with blocks 50 slidable within slots 46 and serving to support it for transverse movement relative to slide 38. Member 48 is provided with rollers 50 engaging the opposite sides of a curved track 52 supported by the members 8. Accordingly, as reciprocating movement is imparted to slide 38 in a direction parallel to rods 6, 10 and 44, the supporting member 48 partakes in this reciprocating movement and at the same time has imparted thereto a transverse movement by means of curved track 52 so that a curvilinear movement relative to base 2 results.

Member 48 is provided with a suitable supporting bracket 54, in which are slidably mounted rods 56 supporting a carriage 58.

The rods are pressed downwardly by springs 60, thus serving to force the carriage toward the base.

Prongs 62 are provided, as indicated in

- 5 Figs. 2 and 3, along the transverse edges of base 2, so that the base securely supports a sheet 64 of the material being tested. Similarly, carriage 58 is provided with prongs 66 serving to securely hold thereon a sheet 10 68 of the material being tested, so that during the operation of the machine sheets 64 and 66 are moved in contact with each other to produce abrasion. By reason of the curvilinear movement of the carriage relative to 15 the base, abrasion is effected which will not be directly in parallelism with either the warp or weft of the materials, if woven materials are used. Instead, an abrasive action comparable to that which occurs in the wearing of 20 clothing by, for example, the abrasion of a sleeve with a coat, such as would occur during the swinging of the arms, will be effected.

By reason of the fact that rod 6 is journaled in frame 4, the entire frame, consisting 25 of members 8 and the carriage and other parts carried thereby, may be swung from the full line position of Fig. 3 to the dotted line position, thereby facilitating the replacement of the materials 64 and 68. At the same 30 time, the current through motor 33 is automatically interrupted by reason of the connection of a link 70 between an arm carried by rod 6 and a suitable switch, indicated diagrammatically at 72.

35 In order to make a determination of the abrasion resulting from a predetermined number of reciprocations of the carriage, a rod 74 is slidably mounted in the frame 4 and is provided with turned ends 76 adapted 40 to contact with the sides of segment 14 during the reciprocation thereof. Rod 74 carries a cam 78 which acts upon a roller 80 carried by a spring pressed rod 82, whereby, upon each reciprocation of segment 14, the counter 45 84 is actuated to register such reciprocation. The materials may be examined after the counter registers any predetermined number of reciprocations.

While there are shown two pieces 64 and 68

50 which were stated to be of the same material, it is obvious that the two pieces may be of different materials, or, alternatively, a piece of fabric may be carried by either the carriage or the supporting base, while the other member 55 is provided with a surface of some suitable abrasive material, so as to determine the action of such abrasive material on the fabric. Instead of fabrics being placed on the machine, it will, of course, be obvious that other 60 materials may be suitably mounted on the carriage and base.

By reason of the provision of segment 14, it will be seen that the connection between block 18 and this segment is not disturbed 65 during the opening of the device for the re-

placement of materials. By reason of this mode of connection, there is no time lost in reassembling the operative parts in order to renew the operation. The use of the automatic switch 72 serves to start and stop the 70 operation accordingly as the carriage is moved to or from its operative position.

What I claim and desire to protect by Letters Patent is:

1. A machine of the character described 75 comprising a support, a movable device, said support and device having opposed surfaces over which materials may be supported in surface contact with each other, a curvilinear guide for the device, and means for imparting 80 reciprocating movements to the device, whereby it is guided in a curvilinear path across the surface of the support.

2. A machine of the character described 85 comprising a support, a movable device, said support and device having opposed surfaces over which materials may be supported in surface contact with each other, a curvilinear guide for the device, means for imparting reciprocating movements to the device, 90 whereby it is guided in a curvilinear path across the surface of the support, and means for yieldingly urging the device towards the support.

3. A machine of the character described 95 comprising a support, a carriage, said support and carriage having opposed surfaces over which materials may be supported in surface contact with each other, a member 100 mounted for linear movement, the carriage being supported by the member for movement relative thereto, means for imparting reciprocating movement to the member, and means for guiding the carriage in a curvilinear path across the surface of the support during the linear movement of said member.

4. A machine of the character described 105 comprising a support having a base portion and a top frame portion pivoted to the base portion, a movable device, said base portion and device having opposed surfaces over which materials may be supported in surface contact with each other, a curvilinear guide for the device, means for imparting reciprocatory movements to the device, whereby it 110 is guided in a curvilinear path across the surface of the base portion, and means mounting the device on the top frame portion whereby it may be removed from cooperation 115 with the surface of the base portion upon pivotal movement of the top frame portion.

5. A machine of the character described 120 comprising a support having a base portion and a top frame portion pivoted to the base portion, a movable device, said base portion and device having opposed surfaces over which materials may be supported in surface contact with each other, a curvilinear guide for the device, means for imparting reciprocatory movements to the device, whereby it is 125

guided in a curvilinear path across the surface of the base portion, and means mounting the device on the top frame portion whereby it may be removed from cooperation with the 5 surface of the base portion upon pivotal movement of the top frame portion, said movement imparting means including connections whereby the operative condition is maintained during pivotal movement of the 10 top frame portion.

6. A machine of the character described comprising a support, a movable device, said support and device having opposed surfaces over which materials may be supported in 15 surface contact with each other, means for guiding the device in a curvilinear path, means for imparting reciprocatory movements to the device, whereby it is guided in a curvilinear path across the surface of the 20 support, and means for registering the reciprocations of the carriage.

7. A machine of the character described comprising a support having a base portion and a top frame portion pivoted to the base 25 portion, a movable device, said base portion and device having opposed surfaces over which materials may be supported in surface contact with each other, and means supporting the device on the top frame portion and 30 guiding it for curvilinear movement across the surface of the base portion, whereby the device may be lifted from the base portion upon pivotal movement of the top frame portion.

35 8. A machine of the character described comprising a support having a base portion and a top frame portion pivoted to the base portion, a movable device, said base portion and device having opposed surfaces over 40 which materials may be supported in surface contact with each other, means supporting the device on the top frame portion and guiding it for curvilinear movement across the surface of the base portion, whereby the device may be lifted from the base portion upon 45 pivotal movement of the top frame portion, and means for imparting reciprocating movements to the device, said means including connections whereby the operative condition is 50 maintained during pivotal movement of the top frame portion.

9. A machine of the character described comprising a support, a carriage, said support and carriage having opposed surfaces 55 over which materials may be supported in surface contact with each other, a member mounted on the support for linear movement, the carriage being supported by the member for movement relative thereto, means for 60 guiding the carriage in a curvilinear path across the surface of the support during linear movement of said member, a continuous flexible element moving in one direction, an element connected to the member and guided for linear movement, and a slide and slideway 65

connection between the flexible element and the last mentioned element whereby continuous movement of the flexible element imparts a reciprocatory movement to the member through the intermediate connections.

In testimony of which invention, I have hereunto set my hand, at Philadelphia, Pennsylvania, on this 27th day of April, 1929.

SOLOMON WEINBERG.
